The ornamental design for a stud handle, as shown and described.

DESCRIPTION

FIG. 1 is a perspective view of a stud handle, showing my new design therefor;

FIG. 2 is a right side elevation view;

FIG. 3 is a left side elevation view;

FIG. 4 is a front side elevation view, it being understood that a rear side elevation view would be a mirror image of this front side elevation view;

FIG. 5 is a top plan view; and,

FIG. 6 is a bottom plan view.
